UNITED STATES PATENT OFFICE.

CARLO U. FINOCCHIARO, OF NEW YORK, N. Y.

FILING DEVICE FOR SOUND-REPRODUCING RECORDS.

Application filed April 29, 1922. Serial No. 557,356.

To all whom it may concern:

Be it known that I, CARLO U. FINOCCHIARO, a citizen of the United States, residing in the city of New York, borough of Manhattan, in the county and State of New York, have invented a new and Improved Filing Device for Sound-Reproducing Records, of which the following is a full, clear, and exact description.

10 My invention has for its object to provide a filing device for sound reproducing records having two series of rods spaced apart, the rods in each series being spaced from each other to afford filing spaces for 15 the records. The two series of rods are preferably disposed one above the other with the forward terminals of the upper set of rods bent upwardly and the forward terminals of the lower set of rods bent 20 downwardly, it being understood that some of the rods in one of the series may be disposed nearer some of the rods in the other series than is the case with the remaining rods, so that records of different diameters 25 may be conveniently accommodated.

Another object of the invention is to provide guides which are disposed in planes extending from one of the series of guides to the other series in which may be retained 30 cards with the titles of the records in the order in which they are disposed between the rods.

Additional objects of the invention will appear in the following specification, in 35 which the preferred form of my invention is described.

In the drawings, similar reference characters refer to similar parts in all the views, in which—

40 Figure 1 is a sectional side elevation of a sound reproducing machine cabinet in which my invention is embodied;

Figure 2 is a fragmentary front elevation of the cabinet shown in Figure 1 with the 45 doors open;

Figure 3 is a plan view of the lower set of rods with the supporting transverse members;

Figure 4 is a perspective view of one of 50 the guide members in which cards with the titles of the records are disposed.

By referring to the drawings, it will be seen that the cabinet 5 is of the usual construction and that it has a space 6 in which 55 the records may be disposed. In this space 6, which is normally closed by the doors 7,

I dispose my rods with their supporting members.

Each set of rods 8 is provided with two transverse members 9 and 10 which serve 60 as the main supports and with an additional transverse member 11. The rods 8 at each side of the transverse members are disposed substantially in the same plane and with their forward ends 8^b bent downwardly and 65 with their terminals 8^c secured to the transverse member 9. The rear terminals 8^d are secured to the transverse member 10. Between these rods 8, there are disposed additional rods 8^a which extend in a plane above 70 the plane in which the rods 8 are disposed. These rods 8^a also have their forward ends 8^e bent downwardly and their forward terminals secured to the transverse member 9. The rear terminals of the rods 8^a are 75 secured to the additional transverse member 11, this additional transverse member 11 being supported by a member 12 which is secured to the transverse member 10. It will be understood that this member 12 may be 80 an extension of one of the rods 8^a. Another set of the rods 8 and 8^a with transverse members is inverted and disposed above the rods 8 and 8^a which have been described, 85 thus forming guides between the upper and the lower rods in which the records 13 and 14 may be disposed, the records 14, which are of less diameter than the records 13, being supported by the rods 8^a and the corresponding rods 8', and the records of 90 greater diameter being supported by the rods 8 and the corresponding rods 8². As has been stated, the upper rods 8' correspond with the lower rods 8^a, and the upper rods 8² correspond with the lower rods 95 8; the upper transverse member 9^a corresponds with the lower transverse member 10, and the upper additional transverse member 11^a corresponds with the lower additional transverse member 11. 100

It will be understood, in the construction which has been described, that the transverse members 9 and 10 and 9^a and 10^a carrying the additional transverse members 11 and 11^a, with the rods 8, 8^a, 8² and 8', 105 may be disposed in the space 6 in the cabinet 5, and the transverse members 9^a and 9 may be secured to the horizontal members forming the top and the bottom of the space 6, and the transverse members 10^a and 10 110 may be secured either to the sides of the cabinet B or to strips 14 which may be

secured to the sides of the cabinet B. In this way, any cabinet of the usual construction may be readily converted so that my invention may be used to file the records 5 in a convenient manner.

In the preferred form of my invention, there is a drawer 15 above the space 6 in the cabinet, this drawer 15 having a glass panel 16 at its forward end, there being 10 disposed in the rear of the said glass panel guide members 17 in which may be disposed cards 18 on which may be written the titles of the records which are disposed immediately below the said guides. These 15 guides 17 are preferably constructed with their lower ends 19 bent at right angles to their bodies to form bases which may be secured to the bottom of the drawer 15 by screws disposed through the orifices 20 of 20 the bases 19, the said screws extending into the bottom of the drawer. In order to more conveniently examine the cards in the guide members 17 and to assist in the disposal of the cards in the said guide members, there 25 are two rows of these guide members, the guide members in the front row being spaced apart and the guide members in the rear row being staggered relatively to the guide members in the front row so that the cards 30 on the guide members in the rear row may be examined by looking between the guide members in the front row. The cards 18 in the guide members 17 may be removed and other cards may be inserted when the 35 record or records filed between the rods immediately below the said guide members are replaced by other records. In the drawer 15 at the rear of the panel members, there is preferably a partition 21 disposed 40 at the rear of the rear panel members 17 which will provide a space in the drawer in which records 22 may be stored when it is not desired to use them frequently.

Having thus described my invention, I 45 claim:

1. In a filing device for sound reproducing records, two sets of rods spaced apart and disposed one set above the other, the rods in the upper set, when in normal position, being bent at their forward ends upwardly, and the rods in the lower set being bent at their forward ends downwardly, and four transverse members to which the terminals of the rods are secured.
2. In a filing device for sound reproducing records, two transverse members, a plurality of rods spaced apart bent at one set of ends and having their terminals secured to the transverse members, additional rods spaced apart bent at one set of ends with their terminals at said ends secure to one of the transverse members, a third transverse member to which the other terminals of the additional rods are secured and means 60 connecting the third transverse member with

the other of the first two mentioned transverse members to support the third transverse member.

3. In a filing device for sound reproducing records, two sets of rods normally spaced apart, the rods in each set when in normal position being bent at one set of ends away from the rods in the other set, four transverse members, the terminals of the rods being secured to the transverse members, and two sets of additional rods, one set of the additional rods having ends bent in the same direction as the bent ends of one of the first mentioned sets of rods with terminals at their said bent ends secured to one of the transverse members, the other set of the additional rods having ends bent in the same direction as the bent ends of the other of the first mentioned sets of rods with terminals at their said bent ends secured to one of the transverse members, two additional transverse members, the other terminals of one set of the additional rods being secured to one of said additional transverse members and the other terminals of the other set of additional rods being secured to the other of said additional transverse members, and means to hold the additional transverse members in position relatively to one of the first mentioned four transverse members.

4. In a filing device for sound reproducing records, two sets of rods, the central portions of the rods in one set extending in the same general direction as the central portions of the rods in the other set, the rods in each set when in normal position being bent at one set of ends away from the other set, and four transverse members to which the terminals of the rods are secured.

5. In a filing device for sound reproducing records, a cabinet, two sets of rods disposed in the cabinet with their central portions extending in the same general direction, the rods in each set being bent at their forward ends away from the rods in the other set, four transverse members to which the terminals of the rods are secured, the transverse members being secured to the cabinet.

6. In a filing device for sound reproducing records, a cabinet, two transverse members secured to the cabinet, a plurality of rods spaced apart and bent at their forward ends and having their terminals secured to the transverse members, additional rods spaced apart bent at their forward ends with their terminals at their said ends secured to one of the transverse members, a third transverse member to which the other terminals of the additional rods are secured, and means supporting the third transverse member relatively to the other transverse members.

7. In a filing device for sound reproduc-

ing records, a cabinet, two sets of rods spaced apart and disposed in the cabinet, the rods in each set being bent at one set of ends away from the rods in the other set, 5 four transverse members secured to the cabinet, the terminals of the rods being secured to the transverse members, two sets of additional rods, one set of the additional rods having their forward ends bent in the same 10 direction as the bent ends of one of the first mentioned sets of rods with their terminals at their bent ends secured to one of the transverse members, the other set of the additional rods having their forward ends 15 bent in the same direction as the bent ends of the other of the first two mentioned sets of rods with their terminals at their bent

ends secured to one of the transverse members, two additional transverse members disposed in the cabinet, the other terminals of one set of the additional rods being secured to one of the additional transverse members and the other terminals of the other set of additional rods being secured to the other of the additional transverse members, and 20 means to support the additional transverse members. 25

8. In a filing device for sound reproducing records, a plurality of guides in which cards with titles of records may be removably disposed, and means for filing records having the said titles in the planes of the guides respectively. 30

CARLO U. FINOCCHIARO.
